UNITED STATES PATENT OFFICE.

HOMER A. HILL, OF LEBANON, TENNESSEE.

FLYING-MACHINE.

1,308,632.

Specification of Letters Patent. Patented July 1, 1919.

Application filed August 22, 1918. Serial No. 250,999.

To all whom it may concern:

Be it known that I, HOMER A. HILL, a citizen of the United States, residing at Lebanon, in the county of Wilson and State 5 of Tennessee, have invented new and useful Improvements in Flying-Machines, of which the following is a specification.

This invention relates to flying machines, and particularly to flying machines of the 10 helicopter type, one object of the invention being to provide a flying machine of this character embodying a combined supporting and propelling means consisting of a series of superposed propellers adjustable to different 15 working positions for a lifting action or a combined lifting and propelling action, and which also may be rotated at various speeds to govern the ascent and descent of the craft.

A further object of the invention is to 20 provide simple, reliable and efficient means for driving and adjusting the propellers and maintaining a determined relationship between the same and the car of the craft, whereby stability is secured.

25 The invention consists of the features of construction, combination and arrangement of parts, hereinafter fully described and claimed, reference being had to the accompanying drawings, in which:—

30 Figure 1 is a side elevation, with parts in section, of a helicopter flying machine embodying my invention, showing the rotating propellers in lifting position.

Fig. 2 is a top plan view of the same.

35 Fig. 3 is a vertical longitudinal section through the upper portion of the car and the lower portion of the tilting propeller carrying frame.

Fig. 4 is a vertical longitudinal section 40 through the upper portion of the propeller carrying frame and the hubs of the two upper propellers.

Fig. 5 is a sectional plan view on the line 5—5 of Fig. 4.

45 Fig. 6 is a partial sectional view of the blade.

In carrying my invention into practice, I provide a car 1 of any suitable form and construction, but preferably of substantially 50 conical form as shown, and having a carriage or wheel support 2 for supporting the machine when at rest upon the ground and adapting the same to be moved from place to place upon the ground or to run

along the surface of the ground under its 55 own power. This car is designed to contain suitable accommodations for the pilot and passengers, if any, the driving motor (not shown), and the required mechanism for controlling the machine in flight. As 60 shown, the body 1 may have mounted thereon a vertical rudder 3 for steering the machine laterally, which rudder may be operated by any suitable type of operating means. 65

Supported by the car 1 is a mast 4 carrying a series of superposed sets of propellers, each set consisting of an upper propeller 5 and a companion lower propeller 6, the propellers 5 and 6 being constructed and 70 arranged to rotate simultaneously in opposite directions. In the present instance I have shown the use of two sets or pairs of propellers 5 and 6, but any number may be employed, according to the size of the machine and other conditions. 75

Each propeller 5 or 6 is of similar construction, with the exceptions hereinafter mentioned, and comprises a hub or drum 7 provided with a series of equidistantly 80 arranged radial arms 8 carrying propeller blades 9, each propeller being shown in the present instance as having four blades arranged at an angle of 90° to each other. The arms 8 may be of a suitable truss construction to secure proper strength and resistance to strain, and each propeller blade 9 is preferably of oblong rectangular form and provided at its outer end with a flange 10 and along its lower edge with a flange 11. The blades 9 are set at a proper angle 85 of inclination to gather and compress the air as they revolve, and the flanges 10 and 11 face forward in the direction of rotation of the blade and act as air gathering and retaining elements to hold the air confined and compressed against the body of the blade for a sufficient period to secure the proper dynamical reaction for supporting effect. 95

As each propeller 5 rotates in one direction, while its companion propeller 6 rotates in the opposite direction, it will be understood that the body portions and flanges 10 and 11 of the propellers 5 incline and 105 face in one direction, while the body portions and flanges of the propellers 6 incline and face in the opposite direction to those of

the propellers 5. Thus the blade of each propeller 5 or 6, as it revolves, travels at a determined pitch or angle of incidence and compresses the air continuously in its course 5 of rotation for a supporting action.

The hub or drum 7 of each propeller 5 is suitably fixed, as by means of a spider formed of a sleeve 12 and radiating arms 13, to a propeller shaft 14 extending through

- 10 the mast and the hubs of the propellers forming part thereof, while the hubs 7 of the propellers 6 are driven by suitable gearing from said shaft, so as to effect the rotation of the propellers 6 in the opposite direction to the direction of rotation of the propellers 5 and shaft 14. To this end the shaft 14 is provided with a bevel drive gear 15 for each propeller 6, said gear 15 meshing with one member 16 of a double bevel gear journaled upon a stub shaft 17, carried by a fixed part of the mast 4, the other bevel gear member 18 of which double bevel gear meshes with a bevel gear 19 on the hub or drum 7 of the propeller 6, whereby said propeller is driven.

The mast structure 4 comprises a series of supporting and bearing disks or heads 20 connected and held in fixed relation by bars or rods 21, the heads or disks 20 being arranged in pairs with the heads or bearing members of each pair arranged above and below the respective drums or hubs 7 of the propellers. The meeting faces of the adjacent heads of the propeller hubs are grooved 35 to form raceways 22 between which are interposed anti-friction bearing balls or members 23, operating to center and maintain the drums in proper working relationship while permitting of free and easy rotary motion thereof. As shown, the frame bars 21 which connect the bearing heads 20 associated with the hubs 7 of the propellers 6 extend through said hubs and serve as supports for the double bevel gears of the propeller drive gearing, said hubs revolving about the said frame bars in an obvious manner. The mast includes the upper disk or head 21' which is fixed to the upper end of the shaft 14 and between which and the adjacent propeller hub 7 are arranged anti-friction bearings of the type described.

The mast also includes a lower head or bracket 24 forming a base support for pivotally connecting the same with the reduced 55 upper end of the conical car 1, said bracket 24 being shown in the present instance as connected by horizontal transverse pivots 25 with bracket members 26 attached to the sides of the car 1, whereby the mast and propellers are adapted to be turned in a fore and aft direction. A drive shaft 27 is journaled upon the car 1 and driven in any suitable manner from the motor, and this shaft 27 is coupled at its lower end to the propeller shaft 14 by means of a joint 28 of suit-

able construction to connect said shafts for a driving action, while permitting tilting motion of the shaft 14 with the mast. Thus it will be understood that the mast and propellers may be inclined at a working angle 71 of inclination with respect to the car 1, which normally hangs in a vertical position, without interfering in any manner with the driving action between the motor and the propellers.

For the purpose of tilting the mast and propellers any suitable mechanism is provided comprising a threaded shaft 29 with which engages a nut 30 provided with a hand wheel 31, said nut being disposed between bracket members 32 on the car which are apertured for the passage of the shaft 29, whereby said shaft may be moved upwardly or downwardly and locked by the nut in adjusted position. A link 33 connects the shaft 29 with the bracket 24, whereby through the adjustments of the shaft the mast and propellers may be tilted and locked at any desired angle of working inclination relative to the car 1.

In the operation of launching the craft, the propellers, arranged in the normal position shown in Fig. 1, are set into action and revolved at high speed to lift the craft directly from the ground into the air. When the desired altitude is reached the propellers are then tilted forwardly at such an angle that the propeller blades will exert a supporting effect as well as a propelling effect upon the air to drive the machine forward in course of flight. It is obvious that the propelling and lifting effect may be varied and governed by driving the propellers at different speeds and tilting them to different angles of inclination. By reducing the speed of the propellers to a desired degree, the machine may be maintained at a given altitude in the air and driven forward, and by proper tilting motions of the propellers in a fore and aft direction the longitudinal stability of the craft may be maintained, the gyroscopic action of the oppositely rotating sets of propellers giving inherent lateral stability. It will be evident that by proper adjustments of the propellers the craft may be caused to ascend in a direct vertical path or to ascend at an angle, and by reducing the speed of the propellers the craft may be allowed to descend at any desired low rate of speed either in a direct vertical path or at a gliding angle. By also reducing the speed of the propellers to exact sustentation speed, the craft may be made to hover in the air over any given point.

Having thus fully described my invention, I claim:

1. A flying machine comprising a car, a mast connected at its lower end with the car and comprising a series of spaced and super-

posed bearing and supporting heads, pairs of propellers mounted upon the mast, the propellers of each pair being adapted to rotate in opposite directions, said propellers having hubs disposed between adjacent heads and in bearing contact therewith, a shaft extending through the mast and to which the hubs of certain of said propellers are fixed, and drive gearing between said shaft and the hubs of the other propellers for driving said propellers in the reverse direction to the direction of rotation of the shaft.

2. A flying machine comprising a car, a mast pivotally connected at its lower end with the car to tilt in a fore and aft direction, said mast comprising a series of spaced and superposed bearing and supporting heads, pairs of propellers mounted upon the mast, the propellers of each pair being adapted to rotate in opposite directions, said propellers having hubs disposed between adjacent heads and in bearing contact therewith, a shaft extending through the mast, and to which the hubs of certain of said propellers are fixed, and drive gearing between said shaft and the hubs of the other propellers for driving said propellers in the

reverse direction to the direction of the rotation of the shaft. 30

3. A flying machine comprising a car, a drive shaft upon the car, a mast pivoted at its lower end to the car for tilting motion in a fore and aft direction, said mast including a series of spaced and superposed bearing heads, a plurality of pairs of horizontally rotatable propellers having hubs journaled on the mast between the bearing heads, the propellers of each pair being adapted to rotate in opposite directions, a drive shaft 35 extending through the heads and hubs of the propellers and to which the hubs of certain of said propellers are fixed, gearing between said shaft and the hubs of the other propellers for driving said propellers in a 40 direction opposite to the direction of rotation of the shaft, a joint connection between the said drive and propeller shafts to permit the latter to be driven from the former and also to be tilted in a fore-and-aft direction, and means upon the car for tilting the mast and propellers in a fore and aft direction. 45 50

In testimony whereof I affix my signature.

HOMER A. HILL.
